UNITED STATES PATENT OFFICE

2,555,626

ATTIC LOUVER

Henry Avers and James W. Ground,
Stillwater, Okla.

Application June 9, 1949, Serial No. 98,032

5 Claims. (Cl. 98—121)

1

This invention comprises novel and useful improvements in attic louvers and more specifically pertains to a ventilation louver construction for walls and the like, and generally consists of a louver construction formed of angle iron members rigidly secured together to form a frame together with a series of slanting, parallel vertically spaced slats carried by the frame together with a screen secured thereto.

The principal object of this invention is to provide a ventilation louver of a sturdy but simple and inexpensive construction which will satisfactorily admit the passage of air therethrough but will prevent the ingress of rain, snow, the direct rays of the sun and the like.

A further object of the invention is to provide an improved louver construction which is ideally adapted for use with vertical walls or the like, and in which an improved screening is assembled as a part of the louver construction.

A further object of the invention is to provide a louver construction as set forth in the foregoing objects which shall include a condensation and water collecting trough for collecting water impinging and condensing on the slats of the louver, and discharging the same exteriorly of the wall with which the louver is associated.

A still further object of the invention is to provide a louver construction which shall be formed of commercial angle iron structural units and which are assembled readily in an improved relation to lessen the weight and increase the strength of the construction.

These, together with various ancillary features and objects of the invention which will later become apparent as the following description proceeds, are attained by this invention, a preferred embodiment of which has been illustrated by way of example only in the accompanying drawings, wherein:

Figure 1 is an elevational view of a portion of the vertical wall of a barn or similar building with which the improved louver construction is associated;

Figure 2 is a horizontal sectional view taken substantially upon the plane of the section line 2—2 thereof, parts being broken away and omitted;

Figure 3 is a vertical transverse sectional view taken substantially upon the plane of the section line 3—3 of Figure 1, parts being broken away and omitted; and,

Figure 4 is an assembly perspective view of the various elements making up the improved louver construction.

2

Referring now more specifically to the accompanying drawings, wherein like numerals designate similar parts throughout the various views, there is disclosed the improved louver construction indicated generally by the numeral 10 mounted in an opening of a vertical wall 12 which may form a part of a barn or house or the like, it being understood that the louver is customarily recessed in this opening flush with the exterior surface of the wall or partition 12.

The louver construction 10 includes top and bottom rail members 14 and 16, which are of angle iron construction as are also vertical end members 18 and 20 together with vertical intermediate members 22 and 24.

Considering first the intermediate members, it will be seen that these members may conveniently be formed of U-shaped channel members, the web portion of which are provided with a series 20 of coextensive vertically spaced and inclined slots 26 which may be disposed at any suitable angle such as 45° or the like. At their upper and lower ends, the intermediate channel members are provided with horizontally disposed flanges 28 and 30 25 for a purpose which will be later set forth.

The end members 18 and 20 are of L-shaped cross-section and are provided with similar coextensive vertically spaced inclined slots 26, the end members at their upper and lower extremities likewise terminating in horizontally disposed flanges 32 and 34. While the slots 26 of the intermediate members 22 and 24 extend entirely through these members, the corresponding slots of the end members 18 and 20 may either be formed as grooves in the surface of one wall of the angle iron end members, or may comprise slots extending therethrough as desired.

A plurality of slats 36 having their sides extending upwardly as at 38 and downwardly as at 40 respectively have these sides disposed in any convenient angle such as in vertical planes, these slats being disposed through the slots 26 of the intermediate members, and extending into or through the slots 26 of the end members, whereby the slats are firmly mounted in overlapping relation to form vanes or shutters which slope downwardly and outwardly of the louver construction, as shown in Figures 1 and 3.

If desired, the slats may be welded where they engage any of the end or intermediate members in order to increase the rigidity of the construction.

The top and bottom rails 14 and 16 preferably comprise horizontal portions 42 and 44 which have respective vertically upstanding and de-

pending flanges 46 and 48 respectively which are adapted to be disposed substantially flush with the vertical wall surface 12 as will be seen from Figures 1 and 3. At what may be termed the inner side or inner end of the shutters, the top and bottom rails are provided with vertical flanges 50 and 52 which extend inwardly of the shutter. It is intended that the portions 42 and 44 shall be seated upon each of the flanges 28 and 32, and 30 and 34 respectively, and be welded thereto to complete a rigid rectangular framework.

In order to render the rectangular framework of the shutter more rigid, a gusset plate 54 may be welded to the joint formed between each of the end members and a top or bottom rail, as will be readily apparent from Figure 1.

It is proposed to further reinforce and strengthen the framework of the louver construction by adding reinforcing members to the vertical end members, these reinforcing members being likewise of L-shaped construction and being indicated generally by the numerals 56 and 58. Each of these members includes perpendicularly disposed vertical walls 60 and 62, the walls 60 having perpendicular, outwardly extending vertical flanges 64 which are adapted to abut against and be welded to the laterally extending surface of the end members 18 and 20 while the walls 62 are adapted to abut against and be welded to perpendicular, inwardly extending vertical flanges 66 formed on the walls 68 of the end members, as shown in Figure 2. It will thus be seen that the end members are of hollow square construction, to thus form vertical columns or pillars to thereby reinforce the rectangular framework of the louver construction.

In accordance with this invention, a screen 70 of any desired material may extend across the rectangular frame of the louver upon the interior or inner side thereof, and this screen may conveniently comprise a wire screening which is secured between the inwardly extending vertical flanges 66 of the two end members and the walls 62 of the reinforcing members.

The invention further contemplates the provision of the water collection trough disposed beneath the bottom rail, and this trough may conveniently comprise a horizontally disposed plate 72 having an upstanding back or inner flange 74 with integral upstanding end flanges 76, and a depending outer or front flange 78. As shown best in Figure 3, the water collection trough is mounted upon the inside of the wall in which the ventilated louver construction is disposed, with a vertical flange 74 disposed inwardly of the screening 70, with the plate 72 underlying the bottom rail 16 and with the forward flange 78 being welded or otherwise secured to the rear surface of the depending flange 48 of the bottom rail. Any suitable means may be provided for conducting moisture collected in this collecting trough to the exterior surface of the wall with which the louver is constructed.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact

construction shown and described, but all suitable modifications and equivalents may be resorted to, falling within the scope of the appended claims.

5 We claim:

1. A ventilating louver for walls comprising a rectangular frame having horizontal angle iron top and bottom rails connected by vertical angle iron end members and intermediate channel members, coextensive, vertically spaced, inclined slots in each of said end and intermediate members, a plurality of slats received in said slots, horizontal flanges on the ends of each of said end and intermediate members, said top and bottom rails being secured to said horizontal flanges, said end members being L-shaped in cross-section, and L-shaped reinforcing members secured to the sides of the L-shaped end members to form box-shaped vertical pillars, said end members and reinforcing members having each a parallel vertical flange on one side parallel to their other sides, the flanges on one member being welded to the other side of the other member.

2. The combination of claim 1 including a screen secured to said frame between the flange on the end members and the other side of the reinforcing members.

3. The combination of claim 2 including vertical flanges on said top and bottom rails secured to said screen.

4. The combination of claim 3 including a vertical depending flange on said bottom rail and a condensate collecting channel having a vertical flange secured to said depending flange, a trough beneath said bottom rail and a vertical upstanding flange on said channel.

5. A ventilating louver for walls comprising a rectangular frame having horizontal angle iron top and bottom rails connected by vertical angle iron end members and intermediate channel members, coextensive, vertically spaced, inclined slots in each of said end and intermediate members, a plurality of slats received in said slots, horizontal flanges on the ends of each of said end and intermediate members, said top and bottom rails being secured to said horizontal flanges, a vertical depending flange on said bottom rail and a condensate collecting channel having a vertical flange secured to said depending flange, a trough beneath said bottom rail and a vertical upstanding flange on said channel.

HENRY AVERS.
JAMES W. GROUND.
